UNITED STATES PATENT OFFICE

GEORGE M. SCHOTT, OF CINCINNATI, OHIO, ASSIGNOR TO THE CINCINNATI GALVANIZING COMPANY, OF CINCINNATI, OHIO, A CORPORATION OF OHIO

DESIGN FOR A CORNER BRACKET FOR CARD TABLE

Application filed August 11, 1930. Serial No. 36,628. Term of patent 7 years.

To all whom it may concern:

Be it known that I, GEORGE M. SCHOTT, a citizen of the United States of America, and a resident of Cincinnati, in the county of Hamilton and State of Ohio, have invented a new, original, and ornamental Design for Corner Bracket for Card Table, of which the following is a specification, reference being made to the accompanying drawing, forming a part thereof.

Fig. 1 is a perspective view of the bracket, showing my new design.

Fig. 2 is a side elevational view of the bracket.

I claim:

The ornamental design for a corner bracket for card table, as shown.

GEORGE M. SCHOTT.
